UNITED STATES PATENT OFFICE.

ROBERT J. DEANS, OF BROOKLYN, NEW YORK.

SHINGLE CONSTRUCTION.

Application filed January 8, 1927. Serial No. 159,803.

This invention relates generally to roof coverings, and has more particular reference to a novel type of roofing shingle.

The invention has for an object the provision of an improved roofing shingle of metal, composition, or the like, which may be easily and readily attached to a roof, and which will act more efficiently in preventing leaks.

For further comprehension of the invention, and of the objects and advantages thereof, reference will be had to the following description and accompanying drawing, and to the appended claims in which the various novel features of the invention are more particularly set forth.

Referring to the drawing forming a material part of this disclosure:

Fig. 1 is a plan elevation of a roof shingle constructed according to this invention.

Fig. 2 is a fragmentary view of a strip of material cut by a die stamping out the shingles of this invention.

Fig. 3 is a fragmentary plan view of a roof structure constructed with the invention shingles.

Fig. 4 is a vertical sectional view taken on the line 4—4 of Fig. 3.

Fig. 5 is a fragmentary plan view of a modified form of the invention shingle.

The reference numeral 10 indicates generally a sheet of material after being cut by a die not shown on the drawing, into a plurality of shingles 11. The various elements composing the shingle are so arranged that a minimum waste of material occurs, indicated generally by the space 12 between the shingles.

The shingle body 13 is preferably of rectangular shape, and integral therewith on one edge, on the ends thereof are tongues 14. On the opposite edge of the shingle body, integral therewith, is a central tongue 15 formed with a slot 16 on each side. Attention is directed to the material between the slots 16, which is quite large so as to add to the strength of the tongue 15. The shingle body 13 is also formed with a pair of elongated apertures 17 parallel to the side 50 of the shingle body having the tongues 14, and the inner edges 18 of the apertures 17 are on a line drawn parallel to the shingle body sides and through the inner edge of the slots 16, as indicated in Fig. 3 of the drawing by dotted line 20.

In forming the roof structure with the

shingles, they engage each other as clearly shown in Fig. 3. The tongue 14 of one shingle engages the slot 17 of an adjacent shingle, and the side of one shingle engages 60 the slot 16 of an adjacent shingle. Nails 21 serve to fasten the various shingles to a roof.

In forming the arrangement disclosed in Fig. 3 the lower course of shingles A are first placed in position and fastened thus by the said nails 21. The second course of shingles B are next placed in position by bowing each shingle, first transversely and slipping the tongues 14 of shingles A thru the slots 17, and next longitudinally and slipping the ends of the tongues 15 beneath the shingles A. The course of shingles B is then nailed 70 against displacement. Course C and all later courses are similarly arranged. Shingle C' clearly shows the tongues 14 of shingles B' slipped thru the slots 17 thereof, and the ends of the tongue 15 thereof slipped beneath the shingles B'.

In the modified form of the invention shown in Fig. 5, the shingle body 13' has tongues 14' pivotally attached, and is also provided with a pair of slots 17' having inner ends 18 as explained in the preferred form. The slots 17' are formed with enlarged serrated outer ends 22. Laying a roof with these shingles is very similar to the preferred form, except that after the tongues 14' engage the slots 17' the tongues 14' are diagonally swung on their pivots to engage the serrated outer ends 22. The theory being that an oblique joint is stronger than a rectangular joint.

While I have illustrated and described my invention with some degree of particularity, I realize that in practice various alterations therein may be made. I therefore reserve the right and privilege of changing the form of the details of construction, or otherwise altering the arrangement of the correlated parts without departing from the spirit or the scope of the appended claims.

Having thus described my invention, what I claim as new, and desire to secure by United States Letters Patent is:

1. A device of the class described, comprising a shingle body of rectangular shape, a pair of tongues integral on one edge thereof, on the ends thereof, a central tongue integral on the opposite edge, and formed with a slot on each side, the said shingle body being formed with a pair of elongated

apertures parallel to the side of the shingle having the pair of tongues, and the inner edges of the elongated apertures being in line with the inner edges of the slots of the 5 central tongue, distance being measured from the shingle body sides.

2. A device of the class described, comprising a shingle body of rectangular shape, a pair of tongues integral on one edge thereof, 10 on the ends thereof, a central tongue integral on the opposite edge, and formed with a slot on each side, the distance between the inner edges of the slots being large, the said shingle body being formed 15 with a pair of elongated apertures parallel to the side of the shingle having the pair of tongues, and the inner edges of the elongated apertures being in line with the inner edges of the slots of the central tongue,

distance being measured from the shingle 20 body sides.

3. In a device of the class described, a shingle comprising a body portion having spaced slots therein, upwardly disposed tongues on the adjacent corners of one end 25 of said body portion, and a central tongue on the other end of said body portion, said body portion being provided with side notches extending between the extremities of said central tongue and the adjacent end of 30 body portion, said notches being terminated in longitudinal alignment with the inner end of the slots of said body portion and the ends of said central tongue being disposed downwardly relative thereto.

In testimony whereof I have affixed my signature.

ROBERT J. DEANS.
